THERMOSTATIC RADIATOR VALVE

Edward J. Donnelly, Everett, Mass.

Application December 2, 1932, Serial No. 645,373

4 Claims. (Cl. 236—62)

This invention relates to improvements in radiator valves and has for its object to provide a valve of simple construction which will operate automatically to permit air to escape from the valve, to prevent air from entering the valve, and to prevent steam and water from escaping from the valve.

Another object of the invention is to embody in the structure of the valve a movable valve member constructed as a float and normally resting in an open or unseated position upon a thermostatic element which upon being heated by steam which enters the valve from a radiator to which the valve is attached, is adapted to expand automatically and thereby bend in a manner to lift the valve member causing the latter to be seated and thereby preventing steam from passing through the valve and being discharged therefrom.

Another object of the invention is to provide a means for preventing the thermostatic element from becoming displaced from its normal position or becoming distorted when the valve is being cleaned and for at the same time determining at a glance as to whether said thermostatic element is correctly positioned to function effectively.

Still another object of the invention is to provide a valve in which the valve seat members although closely associated with each other at the top of the valve are nevertheless separable from each other and can be replaced independently if the occasion demands.

The invention consists in a valve as set forth in the following specification and particularly as pointed out in the claims thereof.

Referring to the drawing:—

Fig. 1 represents a side elevation of a radiator valve embodying my invention.

Fig. 2 is a central vertical section taken on the line 2—2 of Fig. 1, looking in the direction of the arrow on said line.

Fig. 3 is a detail horizontal section taken on the line 3—3 of Fig. 2.

Like numerals refer to like parts throughout the several views of the drawing.

In the drawing, 5 represents a casing comprising a base portion 6 and an upper portion 7, the latter being detachably secured to the base portion by having screw-threaded engagement thereat 8. The interior of the casing 5 constitutes a steam chamber 9, and the base portion 6 of the casing is provided with an externally threaded arm 10 having a fluid passage 11 extending therethrough and communicating with said chamber.

Mounted within the steam chamber 9 is a thermostatic element 12, one end portion of which is rigidly secured to a disc 13 by means of a rivet 13'. The disc 13 rests loosely within the casing 5 at the bottom of the chamber 9. The thermostatic element 12 is bent at 14 into semi-circular

form and prior to being mounted in the chamber 9 is heat treated in a well-known manner to approximately 380° temperature and to a predetermined form in order that said element will always be accurate in its operation and will not become distorted while in use. Resting loosely upon the upper free portion of the thermostatic element 12 is a movable valve member 15 embodying therein a buoyant member or float 16 and pin 17, the latter terminating at its upper extremity in a conical portion 18 which is adapted to co-operate with a valve seat 19 formed at the lower end of a port 20 provided in a bushing 21 which is mounted in the upper portion 7 of the casing 5. The bushing 21 is held securely clamped upon the member 7 of the casing 5 by means of a nut 22 which is located upon the exterior of the casing and has screw-threaded engagement with the bushing, and the port 20 is located upon the median axial line of said bushing.

The float 16 is of slightly less diameter than the diameter of the interior of the upper casing member 7 so that while resting upon the upper portion of the thermostatic element 12 the float is guided during its upward and downward movements by the interior wall of the chamber 9.

The upper end portion of the pin 17 projects into a passage 23 provided in the bushing 21 beneath the valve seat 19 and said passage forms a guide for the upper portion of the movable valve member 15. There is sufficient clearance between the periphery of the pin 17 and the wall of the passage 23 to permit air to pass therebetween.

Detachably secured to the nut 22 is a cap 24 which preferably has screw-threaded engagement with the periphery of said nut and is seated against a shoulder 25 provided upon said nut. The bushing 21, nut 22 and cap 24 are assembled in such a manner as to provide a valve chamber 26 therebetween with which the port 20 communicates. A gravity actuated valve member 27 constructed in the form of a disc rests loosely within the chamber 26 upon a seat 28 provided at the upper extremity of the nut 22, and a space is provided between the under surface of said valve member and the upper extremity of the bushing 21, said space forming a portion of the chamber 26. A port 29 is provided in the cap 24 communicating with the chamber 26.

It is evident that it is desirable occasionally to clean the valve upon the interior thereof and remove from the steam chamber 9 foreign particles such as rust and dirt which may have accumulated therein. At such times it is necessary to exercise considerable care so as not to disturb the position of the free end portion of the thermostatic element 12, as to do so would seri-

ously affect the operation of the valve. To prevent such an occurrence and also to provide a means whereby the normal position of the thermostatic element may be established, I provide a positioning member 30 constructed of the same material as the thermostatic element 12 and also adapted to function as a thermostatic element. The positioning member 30 rests upon the upper surface of the lower portion of the element 12 and is secured thereto and to the casing member 6 by the rivet 13. The positioning member 30 is furthermore so formed that when it is subjected to heat that the upper portion thereof will bend or flex toward the left in Fig. 2. A rectangular opening 31 is provided in the positioning member 30 to receive a tongue 32 formed at the upper extremity of the thermostatic element 12 and preferably when the thermostatic element 12 is located in its normal position the under surface of said tongue rests upon the lower edge of the opening 31 and a front edge 33 of the thermostatic element 12 rests against a face of the positioning member 30. The positioning member 30 may therefore be utilized at any time to determine whether the element 12 is correctly positioned, or not, within the steam chamber 9.

In the operation of the valve, the upper portion of the positioning member 30 will flex toward the left in Fig. 2 and the free end of the thermostatic element 12 will flex upwardly and toward the right, thereby freeing the tongue 32 from the opening 31 and preventing interference between the elements 12 and 30. The further movement of the thermostatic element 12 will cause the latter to function in a manner to be hereinafter more fully explained. When the elements 12 and 30 are located in their normal or interlocked positions and the upper casing member 7 is removed from the base portion 6 for the purpose of cleaning the interior of the steam chamber 9, if the fingers of the cleaner contact with the thermostatic element 12 in a manner to distort the upper or free portion of said element, the positioning member 30, on account of its interlocking engagement with the tongue 22 of the element 12, will act to prevent both a lateral and downward displacement of the upper portion of said element.

The general operation of the valve hereinbefore specifically described is as follows:—Assuming that the valve is attached in the usual well-known manner to a radiator and steam is circulating within the radiator and enters the valve therefrom, the heat of the steam will cause the thermostatic element 12 to bend or flex at which time the upper free end portion thereof will move upwardly lifting the movable valve member 15 and causing the conical portion 18 of the pin 17 to contact with the valve seat 19 thereby preventing steam from within the chamber 9 from being discharged through the port 20, chamber 26 and port 29 to the atmosphere. When there is no steam within the radiator and chamber 9 of the valve 5 and both are cold, the gravity actuated valve member 27 will rest upon the valve seat 28 thereby closing the port 20 from above and preventing air from entering the steam chamber 9 and radiator.

If, on the other hand, there is air within the radiator and the casing 5 to the extent that said

air prevents the efficient circulating of the steam through the radiator, said air will cause the valve member 27 to rise slightly from its seat 28 thereby allowing said air to pass outwardly from the chamber 9 through the port 20, chamber 26, and the port 29, to the atmosphere, until such time as said air is removed from the radiator, whereupon the incoming steam entering the radiator and casing 5 will again cause the thermostatic element 12 to flex, as hereinbefore mentioned, and again lift the movable valve member 15 and cause the latter to close the port 20.

During the operation of the movable valve member 15 the float 16 and pin 17 are guided effectively to cause the conical portion 18 of said pin 17 to engage the valve seat 19 by the interior wall of the upper casing member 7 and the wall of the passage 23.

If for any reason water enters the casing 5 from the radiator and reaches the level of the float 16, the movable valve member 15 will be actuated by the water to close the port 20, thereby preventing said water from being discharged from the casing through the port 29.

I claim:

1. A valve of the character described having, in combination, a casing having a steam chamber therein provided with a port communicating with the atmosphere, a thermostatic element mounted within said chamber, a buoyant valve member 30 mounted upon said thermostatic element and actuated by the latter to open and close said port, and other thermostatic means normally interlocking with said first-named thermostatic element whereby the normal position of the latter 35 may be established.

2. A valve of the character described having, in combination, a casing having a steam chamber therein provided with a port communicating with the atmosphere, a thermostatic element mounted within said chamber, a buoyant valve member mounted upon said thermostatic element and actuated by the latter to open and close said port, and other thermostatic means for maintaining the normal position of the first-named 45 thermostatic element at a predetermined location.

3. A valve of the character described having, in combination, a casing having a steam chamber therein provided with a port communicating with the atmosphere, a thermostatic element mounted within said chamber, a buoyant valve member mounted upon said thermostatic element and actuated by the latter to open and close said port, and other thermostatic means to prevent the 55 flexible portion of the first-named thermostatic element from becoming displaced laterally and downwardly from its normal position.

4. A valve of the character described having, in combination, a casing having a steam chamber 60 therein provided with a port communicating with the atmosphere, a thermostatic element mounted within said chamber, a buoyant valve member mounted upon said thermostatic element and actuated by the latter to open and close said port, and another thermostatic element within the steam chamber and normally interlocked with said first-named thermostatic element whereby the normal position of the latter may be maintained at a predetermined location.
